Attala, Tenn.

UNITED STATES PATENT OFFICE.

PAUL DILLING, OF CHICAGO, ILLINOIS.

APRON TIE.

Application filed October 30, 1922. Serial No. 597,814.

To all whom it may concern:

Be it known that I, PAUL DILLING, a citizen of the United States, residing at Chicago, in the county of Cook and State 5 of Illinois, have invented a new and useful Improvement in Apron Ties, of which the following is a specification.

My invention relates to improved means for tying aprons, such as are worn by 10 butchers for example, in a manner to cause the apron to fit snugly and comfortably about the body of the wearer; and it is fully described in the specification and illustrated in the accompanying drawing, 15 in which—

Figure 1 is a broken view in rear elevation of an apron of the class referred to, provided with my improved tie;

Figure 2 is a similar view of the apron 20 showing the eyelets provided in the ends of its waist-band for receiving hooks on opposite ends of the elastic tying-band;

Figure 3 is an enlarged broken view showing one end-portion of the elastic band 25 carrying a hook-device of preferred construction adjustably provided on the strap; and

Figure 4 is a perspective view of the hook-device.

The primary object of my improvement 30 is to supplant the usual tapes extending from the edges of the apron for wrapping and tying about the body of the wearer, and which are objectionable since they tend to become snarled in laundering, consuming time and work to unsnarl them and to become caught in the washing-machine, whereby they are liable to be torn off and to tear the apron.

My device comprises a relatively wide 40 rubber strap 4 adjustably carrying hook-devices 5 on its opposite-end portions to engage eyelets 6 in the waist-band 7 of the apron 8 when the latter is on the person 45 of the wearer, in which position of the apron the eyelets are opposite each other. The hook I provide is that most clearly illustrated in Fig. 4. It consists of a tubular bar 9 having a serrated tongue 10 on

its forward edge; and a rectangular loop 50 11, on which the hook 12 is formed to project centrally, is confined in the bar to extend forwardly therefrom. In the bar is similarly confined a like but transversely somewhat narrower loop 13; and between 55 the two loop-sections so confined in the hollow bar is pivotally confined the corresponding member of a loop 14 having a keeper 15 formed thereon.

To apply the hook-device to the band 60 4, an end of the latter is inserted through the three loops 11, 14 and 13 to extend over the bar 9, in which position the teeth of the tongue 10 engage the under face of the strap 4 to prevent withdrawal thereof. 65

With a hook-device provided on each end-portion of the elastic strap, to apply my improved device to its tying purpose on an apron upon the person of the wearer, the hooks 12 are respectively passed through 70 the opposite eyelets 6, whereupon the loops carrying the keepers 15 are turned to press the keepers over the respective hooks to grip the apron-band at the eyelets between the hooks and keepers for preventing accidental unhooking of the tie. 75

One length of the strap 4 will serve for tying the same size of apron about wearers thereof of varying proportions within a wide range and to hold the apron snugly 80 and comfortably in place about the person, because of the elasticity of the strap and the adjustability of the hook-devices thereon.

I claim:

In a device of the class described, a garment having an opening therein adjacent an edge thereof, a strap adapted to encircle the upper edge of such garment, a clasp adjustably carried by said strap comprising a tubular member, a loop pivoted in said member, a hook pivoted in said member and engageable with said opening, and a keeper pivoted in said member and engageable with said hook to retain the 95 same in said opening.

PAUL DILLING.
